MEANS FOR MAKING REGISTERED PRINTS

Harry C. Jones, New York, N. Y.

Application May 16, 1929. Serial No. 363,467

21 Claims. (Cl. 95—76)

This invention relates to improvements in commercial photographic printing apparatus and more particularly to the means used in securing a variety of plates in predetermined relative positions within frames subject to transference to a machine for the printing operation.

The word "plate" is used broadly to include both positive and negative elements, the term "negative" referring to either a rigid or flexible plate, film or the like, made of any transparent or translucent material, as glass, celluloid or similar substance, paper or textile fabrics treated to permit the passage of light, and bearing images or legends, inscribed manually or mechanically, or deposited photographically, of any subject matter, or having objects attached in a manner to be reproduced by photo-printing.

A "positive" is to be construed as a receptive element of corresponding nature, sensitized to receive a photographic image from a negative held in juxtaposition and subjected to actinic light.

One of the objects of the invention is to provide a frame having distinct and wholly independent portions, each suited to receive a separate negative bearing registering marks and having means whereby the portions of the frame are relatively movable, in the same plane, both rectilinearly and transversely, that is vertically 30 and horizontally with respect to an upright machine, and also angularly, whereby the register marks on each portion may be brought into absolute correspondence with register marks fixed on a master frame superposed on portions of 35 the negative carrying frame.

A further feature is in the provision of means for transferring the negative frame to a holder having connection with a suction means for producing a partial vacuum and provided with a 40 marginal seal, the holder and frame being transferable as a unit to a registration plate having means for adjusting the unit in accordance with marks fixed upon it and thereafter held fixedly by clamp dowel engaging arms, carried by the 45 unit, so that the unit may be placed in exact correspondence upon dowels on the face of a photo-printing machine.

Other objects, such as direct and positive clamping devices of ready and instant application, novel nonmetallic clamp strips to contact the edge of glass plates, and other improved advantageous features, which will become apparent as the description progresses, are accomplished by the novel construction, combination and arrangement of parts as hereinafter described and

shown in the accompanying drawings, constituting a material part of this disclosure, and in which:

Figure 1 is a top plan view of a two part plate holder frame provided with means for adjusting 60 one part relative to the other, both parts having plate receiving recesses, and means for confining plates therein, each plate being provided with registry marks.

Figure 2 is a similar view of a master frame 65 having clamping means to engage the plate holder frame when superposed, and provided with fixed registry lines to which the parts of the plate holder are adjusted.

Figure 3 is a plan view of a holder apertured 70 in conformity with the openings in the plate holder frame, part of one of which is shown as seated on a sealing blanket resting on the holder which is provided with clamping means and extending adjustable arms.

Figure 4 is a similar plan view of the same parts as disposed on a transfer plate having means for adjusting the frame and holder to agree with marks arranged in known relation to a photo-printing machine provided with dowels to engage 80 openings in the holder arms which are clamped when registration has been effected.

Figure 5 is an enlarged sectional view of the frame adjusting means the section being taken on line 5—5 of Fig. 1.

Figure 6 is a similar fragmentary sectional view taken on line 6—6 of Fig. 3.

Figure 7 is a view similar to Fig. 1 but showing yielding blankets interposed between the frame parts and a supporting plate on which they are seated.

Figure 8 is a view showing the parts indicated in Fig. 7 as disposed upon a holder shown in Fig. 3.

Figure 9 is a plan view of a device as seen in Fig. 8 but showing a modified plate adjusting means.

Figure 10 is a similar view of the same parts as mounted on a transfer plate.

Figure 11 is an enlarged cross sectional view taken through one of the non-metallic clamps as disposed within the confines of a sealing device.

The devices shown in either Figs. 1 and 7 are composed of two substantially like frames 15 and 16 provided with continuous recesses 15'—16' suited to receive plates 17 and 18 bearing registry marks 19—20 and 19'—20' at their respective side and end edges, these plates being securely held in the frames by clamps 21, disposed preferably at 110

- opposite corners and set at least flush with the faces of the frame.
- Extending from the side of the frame 15, near its ends, towards the frame 16, are a pair of lugs 23, and rigidly attached to the adjacent member of the frame 16 is a bar 24 reaching outwardly beyond the frame at each end both of which are slotted to receive sleeves 25 pivoted on the points of opposed screws 26 set in the bar ends.
- Passing freely through the sleeves 25 are the plain cylindrical portions of adjusting screws 27 having flanged operative heads 27' and fixed collars 28 at the opposite ends of the sleeves, while the threaded portions of the screws engage in blocks 29.
- Also passing through the blocks 29 are the unthreaded end portions of a screw 30 screw-threadedly engaging the lugs 23, the screw having an operating knob 30' by which it may be rotated.
- From the foregoing it will be manifest that the frames 15—16 may be positively moved to a limited amount towards and from each other, whether in parallelism or at moderate angles, and furthermore the frames may be shifted relatively lengthwise.
- A master frame, generally designated by the numeral 35 is provided with means carrying a single central longitudinal registry line 36 and a transverse line 37 disposed to register with the registry marks 20' of the frame 16 when placed thereover with its edges in registration, while the line 36 will register with the marks 19 of the frame 16.
- Clamping means, as at 39, are carried by the frame 35, the same being engageable by studs 31 set in the ends of the frame 16, which after having been tightened, permit shifting of the frame 15, by the means herein described, to cause registration of the marks 20 with the line 37 and the marks 19 with the lines 36.
- After the marks and lines have been brought in perfect registration, the frame 35 is removed, the frames 15—16 are placed upon a transfer plate 40 having openings 41—41' conforming generally to the frame openings.
- Disposed intermediate the registered frames 15—16 and surface of the plate 40 is yielding element 42, such as a rubber blanket having slots 43 through which may be passed clamping means, as the hooks 44 pivoted in recesses in the plate 40 on pins 45, these hooks being engageable with the frame projections 31—31', as seen in Figs. 3, 4 and 8 and in detail in Fig. 6.
- The plate 40, which may be considered as a transfer element, is provided with perforations 46 in its end portions, adjacent to which are slots 47 to adjustably receive bolts 48 by which adjustable arms 49 may be securely clamped in position.
- Perforations 50 in the arms are engageable with dowels 51 set in a plate 52 and also with exactly similar dowels set in the face of the machine to which the previously described devices are transferable.
- The plate 52 is provided with cross marks 53—54 and operative devices, as indicated by the arms 55 engageable in the openings 46 to bring the elements into exact registration thence to be clamped by the bolts 48.
- A series of studs 56, adjustable on the plate 52, provide means for levelling and supporting the plate 40 during adjustment and a marginal seal 57 encloses the space between the plates 40—42, the space being served by a suction tube
- 58 whereby a partial vacuum may be produced between the plates 40—42.
- In Figures 7 and 8 the construction is essentially the same as depicted in Figs. 1 and 3 with respect to the frames and their relative adjusting devices, but in the modification the frames are disposed on an apertured plate 60 and each frame is provided with a border seal 61—61' the spaces between being served by suction tubes 62—62' to produce a vacuum.
- Figs. 9 and 10 disclose one of the negative plates 65 clamped in a fixed position and the other plate 66 provided with set screws 67 adjustable in lugs 68 upstanding from an apertured plate 69 by which the plate may obviously be moved into as many different positions as the plate 17 with which it agrees in registration marks.
- Figure 10 shows the plate 69 as having a marginal seal 70 interposed between it and an apertured plate 71, the enclosed space having leading into it a suction tube 72 by which a vacuum may be produced.
- The preferred form of space sealing means is well indicated in Fig. 11, but is not to be understood in a limiting sense.
- A partial section of a plate support frame 75 is formed with an inreaching lip, in which may be set a thin light sealing element 76 upon which the marginal edges of the plate 78 are seated.
- The edges of the plate are bevelled and held firmly on the frame by a plurality of non-metallic clips 80, such for instance as indurated fiber, hard rubber, or any of the phenol resins, tough, firm and slightly elastic when drawn into engagement by the clamp screws 79.
- These clips are slightly thinner than the plate 78 and outwardly, beyond their opposite edge is a circumambient space 81 surrounded by a sealing member 82 on which another plate may be seated and drawn into desired intimate relation with the plate 75 by producing a vacuum in the space 81.
- Although the foregoing is descriptive of the preferred embodiment of the sealing means, inclusive of the clips and sealing member, it is to be understood that the invention is not confined to the exact structure shown and described, as equivalent devices of widely variant nature may be substituted therefor.
- The foregoing disclosure is to be regarded as descriptive and illustrative only, and not as restrictive or limitative of the invention, of which obviously an embodiment may be constructed including many modifications without departing from the general scope herein indicated and denoted in the appended claims.
- Having thus described the invention, what is claimed as new and desired to secure by Letters Patent, is:—
1. In a device for making registered prints, a pair of frames each provided with means for holding a negative, and connections, including means for adjusting one of said frames in relation to the other frame, whereby to obtain predetermined relative positives of the negatives, said connections being fixed on the respective frames.
  2. In a device for making registered prints, a pair of frames each provided with means for holding a negative, means for adjusting said frames relatively one to the other while in the same plane to produce predetermined relative positions of the negative in said frames, and means for securing said frames in their adjusted positions, said means being fixed on the frames to extend therebetween.

3. In a device for making registered prints, a pair of frames each provided with means for holding a negative, connections and means combined therewith for moving one of said frames in relation to the other frame to produce predetermined positions of one negative relative to another, said frames having vacuum means to hold the negative thereagainst, and means for sealing said frames when the face of a frame is covered by material upon which a photographic print may be taken. 10
4. In a device for making registered prints, a pair of frames each provided with means for holding a negative, means for moving said frames with relation one to the other thereby to obtain predetermined relative positions, a vacuum tube entering between said frames, and means for sealing said frames when the face of a frame is covered by material upon which a photographic print may be made. 15
5. In a device for making prints, a frame to which a negative may be fastened, a second frame carrying a different negative, said frames being arranged in predetermined relation to each other, a third frame provided with a vacuum tube, and means for sealing the first and second mentioned frames within the space exposed to the action of the vacuum tube of the last mentioned frame. 25
6. In a device for making prints, a frame on which a negative may be fastened, a second frame carrying a different negative, said negative frames being arranged in predetermined relation to each other, a third frame provided with a vacuum tube, means for sealing the first and second mentioned frames within a sealed space in the last mentioned frame, and means for registering the last mentioned frame so that it may be placed on a machine for making photographic prints with the negatives in predetermined positions to a sensitized plate disposed on the machine. 30
7. In a device for making prints, a main frame provided with means for holding a plurality of negative frames, and means for moving one of said negative frames to place it in predetermined relative position to another negative frame, said moving means being attached to the adjacent edges of said negative frames. 45
8. In a device for making prints, a main frame provided with means for holding a plurality of negative frames, means for moving one of the negative frames to place it in predetermined relative position to another negative frame, and a sealing means operable when the face of the frame is covered by material upon which a photographic print is desired. 50
9. In a device for making prints, a main frame to which a plurality of negative frames are fastened in predetermined relative positions to each other, and means to secure said main frame on a support frame within a space sealed for vacuum in the first frame. 60
10. In a device for making prints, a frame to which a plurality of negative frames are fastened in predetermined relative positions to each other, means for positioning said negative frames sealed for vacuum within the first frame, and means for registering the first frame so that it may be placed on a machine for making photographic prints with the negative frames in predetermined position. 70
11. A plurality of frames adapted to receive plates bearing registry marks, means to secure the plates within the frames, and means to adjust each frame in lateral and longitudinal relation with the other frame. 75
12. A plurality of recessed frames adapted to receive plates bearing registry marks, means to secure the plates to said frames, means to adjust each frame in lateral and longitudinal relation with the other frame, a master frame bearing registry marks, means to coincide the registry marks of the plates with the registry marks of said master frame, and means to secure said plurality of frames to the master frame. 80
13. A plurality of recessed frames adapted to receive plates bearing registry marks, a master frame bearing registry marks, means to coincide the registry marks on the plates with the registry marks on the master frame, a transfer plate to receive said recessed frames and master frame as a unit, and means to aline said unit with the transfer plate. 90
14. A plurality of recessed frames adapted to receive plates bearing registry marks, a master frame bearing registry marks, means to form the recessed frames and master frame into a temporary unit, means to coincide the registry marks of the plates with the registry marks of the master frame, a transfer plate to receive said unit, and means to place said unit in a predetermined position on the transfer plate. 95
15. A plurality of recessed frames adapted to receive plates bearing registry marks, a master frame bearing registry marks, a covering of resilient material intermediate said recessed frames and master frame, means to cause a partial vacuum intermediate the master frame and recessed frames, means to coincide the registry marks of the plates with the registry marks of the master frame, means to form said master frame and recessed frames into a temporary unit, a transfer plate to receive said unit, and means to place said unit in a predetermined position on the transfer plate. 105
16. A plurality of recessed frames adapted to receive plates bearing registry marks, means to fasten the plates within the recessed frames, means to adjust one frame in lateral and longitudinal relation with the other frame, a master frame bearing registry marks, means to adjust the registry marks on the master frame with registry marks on the plates, resilient material intermediate the recessed frames and master frame for the purpose of sealing, and means to exhaust air from the space intermediate the recessed frames and master frame. 110
17. Frames to receive registered plates, means to adjust said frames relatively to each other, a master frame on which to impose the former frames, resilient material intermediate said frames and master frame, means to engage said frames with the master frame, registered plates attached to the master frame to coincide with the registry marks of the prints, and means attached to the master frame to locate same on a photo printing machine. 125
18. A frame to receive registered plates, resilient material on one face of the frame, means to attach said resilient material to the frame, an additional frame imposed on the first frame, a registered plate attached to said additional frame to coincide with the former registered plates, and a sealing member intermediate said frames enclosing a circumambient space intermediate the resilient member and sealing member from which the air may be exhausted to cause a vacuum therein. 140
19. In a device for making contact prints, a 150

frame provided with means for holding a plurality of negatives, means for moving one of the negatives into a predetermined position relative to another negative, and means for clamping said negatives in their adjusted positions.

5. 20. In the device for making contact prints, a frame for holding one or more negatives, means for adjusting the negatives relative one to another, sealing means between the negatives and 10 said frame, and vacuum tube leading to the space included by said sealing means.

21. In a photographic printing apparatus for making contact prints, an apertured support plate, a plurality of negatives attached to said plate, means for adjusting one negative relative to another, a circumjacent cushion on the margin of 80 said plate, and a suction device operatively combined to enter into the space surrounded by said marginal cushion.
